[57] CLAIM

The ornamental design for a telephone machine with TV receiver, as shown and described.

DESCRIPTION

FIGS. 1 and 2 are respectively front and rear elevational views of a telephone machine with TV receiver showing our new design, and with the handset cradled in the stand;

FIGS. 3 and 4 are respectively left and right side elevational views thereof;

FIGS. 5 and 6 are respectively top and bottom plan views thereof;

FIG. 7 is a top and front perspective view thereof;

FIG. 8 is also a perspective view of the machine in use, with the handset inverted and spaced apart from the stand which is shown alone, and

FIG. 9 is also a perspective view, from a different vantage point, of the machine in use, with the handset inverted and spaced apart from the stand which is shown alone.

FIG. 1
